UNITED STATES PATENT OFFICE.

FREDERICK A. HART, OF NEW BRITAIN, CONNECTICUT, ASSIGNOR TO REMINGTON ACCOUNTING MACHINE CORPORATION, OF NEW YORK, N. Y., A CORPORATION OF NEW YORK.

COMPUTING MACHINE.

Application filed December 10, 1923. Serial No. 679,693.

To all whom it may concern:

Be it known that I, FREDERICK A. HART, citizen of the United States, and resident of New Britain, in the county of Hartford and State of Connecticut, have invented certain new and useful Improvements in Computing Machines, of which the following is a specification.

My invention relates to computing machines.

The main object of the invention, generally stated, is to provide means for preventing unnecessary traveling movements of a cross truck or jumping totalizer without rendering it ineffective to move at proper intervals in the operation of the machine, thereby reducing the wear, strain and noise incidental to such unnecessary movements, and decreasing liability of injury to the machine.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the different views,

Figure 1 is a side elevation with parts broken away and omitted of a combined typewriting and computing machine embodying my invention.

Figure 2 is a detail fragmentary front elevation of the upper portion of the same with parts broken away and omitted.

Figure 3 is a detail perspective view of the lever and detent for holding the cross truck in its advanced position.

Figure 4 is a detail top plan view of the detent and the means for controlling it; the view also showing the typewriter carriage and some of the associated parts.

I have shown my invention embodied in a combined typewriting and computing machine similar to that shown in the patent to John C. Wahl, No. 1,270,471 dated June 25, 1918, except that the computing mechanism, substantially like that shown in said patent, is applied to a more modern style of typewriting machine, in the main similar to the No. 12 Remington machine. However, I have shown only so much of said com-

bined machine as is necessary to arrive at 55 an understanding of my invention in its embodiment therein. It should be understood, however, that the invention is not restricted to its inclusion in such a machine, but may be employed wherever found available in 60 different makes of computing machines.

The present invention is in the nature of an improvement on the structure disclosed in my application Sr. No. 641,807 filed May 28, 1923, which shows the mechanism of the said Wahl patent embodied 65 in a Remington accounting machine and equipped with detent mechanism for the same general purpose as the present invention.

The construction disclosed in said Wahl patent and that embodied in the Remington accounting machine each includes a Remington typewriting machine, the paper carriage of which has connected thereto a main calculator carriage or truck on which a series of so-called vertical totalizers is mounted. A cross or jumping totalizer is carried by a cross truck. Automatically operating means are employed for intermittently picking up 70 and releasing the cross truck, thus alternately moving the latter forward and allowing it to return to normal position during the travel of the typewriter and main carriage or truck across the machine in one direction. These forward and back movements of the cross carriage are sometimes unnecessary, as for example when the operator desires to skip computing columns without writing therein, and result in undue wear, 75 strain, noise and increased liability of injury incidental to such unnecessary movements.

By my present invention I overcome these difficulties by rendering the release of the cross carriage, by the automatically operated pick-up mechanism, ineffective to bring about a jumping back or return of the cross carriage to normal position. I accomplish this by automatically throwing a detent into engagement with the cross carriage. This 80 detent is controlled by the carriage release key which also is effective to release the main carriage from control of its escapement mechanism so that the movement of the detent is incidental to the release of the carriage by said key.

The typewriting machine to which the calculating mechanism is applied as an at-

tachment includes the usual letter keys 1 and numeral keys 2. The latter have their key levers 3 connected with bell crank sub-levers 4 fulcrumed at 5 on the frame of the machine. The upper end of each sublever carries a pin 6 which works in a slot 7 in the heel of the associated type bar 8. The various type bars are segmentally arranged and turn on a pivot wire 9 supported by a slotted type bar segment 10. Each type bar works in a guide slot in the segment and moves upwardly and rearwardly to strike against the front face of a plate 11 supported by a platen frame 12 mounted in the typewriter carriage 13. The lever 3 of each numeral key also is connected through a pull wire 14 with devices of the actuator of the computing mechanism, as fully shown and described in said hereinbefore mentioned Wahl patent.

The heel of each type bar 8 is provided with a contact 15 which coacts with a segmental universal bar 16 as a type bar approaches the printing position and moves said universal bar rearwardly to actuate the dog rocker and thus afford a letter space movement of the typewriter carriage. Thus, the universal bar has rearwardly projecting arms 17 connected to arms 18 which extend upwardly from a rock shaft 19. A centrally disposed arm 20 on the rock shaft is slotted to receive the forward forked end of a link 21, said fork straddling a pin 22 on the arm 20 which crosses the slot in the upper end thereof. The rear end of the link 21 is operatively connected with a dog rocker 23 pivoted at 24 and carrying feed dogs 25 and 26. These dogs coact with an escapement wheel 27 operatively connected with a feed pinion 28 with which a feed rack 29 meshes. The feed rack is mounted on arms 30 pivoted at 31 on the spring driven typewriter carriage 13.

In order to release the carriage from control of its escapement mechanism I have substituted for the means ordinarily employed in the No. 12 Remington machine for example, the release keys and connections shown in the accompanying drawings although from certain aspects of my invention the character of the release keys and their connections are immaterial.

As shown in the drawings there are two carriage release keys 32 and 33 at opposite sides of the carriage. The key 33 is bent to the right from a lever 34 of the first order which carries it, said lever being fulcrumed on a shouldered pivot screw 35. A washer 36 is interposed between the lever 34 and a cast metal bracket 37 that extends fore-and-aft of the machine and is detachably though firmly secured to the carriage 13 by the screw 35 and an additional screw 38. A shouldered screw 39 has its inner end threaded into a tapped opening in the

bracket 37 after passing through a washer 40. The shouldered portion of this screw 39 passes through a slot 41 in the lever 34 and limits the pivotal movement thereof in both directions while the shoulder on the screw bears against the washer. The lower end of the lever 34 is pivoted at 42 to the forward end of a rearwardly extending link 43. This link is pivoted at its rear end 44 to the depending arm of a three-arm lever 45 pivoted by its upper arm at 46 to the carriage. The rearwardly extending arm 47 of this lever extends beneath the feed rack 29 at one end thereof and is adapted to lift the rack out of engagement with its feed pinion 28 when the key 33 is depressed, thereby freeing the carriage from control of its escapement mechanism. A spring 36^a is coiled around the washer 36 and bears at one end against the bracket 37 and at its opposite end against the lower edge of the lever 34. This spring returns the key 33 and the parts directly connected therewith to normal position; a spring 48 causing a re-engagement of the feed rack 29 with the feed pinion.

The bracket 37 is provided with bearings 49 and 50 in which the usual spring returned rock-shaft 51 of the line spacing mechanism is supported for rocking movement by the line spacing handle 52.

A somewhat similar train or releasing connections to those described above are provided at the left-hand side of the machine between the finger key 32 and the feed rack, and the description of one in the main applies to the other. Corresponding parts in the two trains will therefore be indicated by the same reference numerals. The cast bracket 53 at the left-hand side of the carriage is arranged outside of the companion lever 34 instead of between it and the carriage as in the previously described construction, and said lever 34 turns on a hollow shouldered stud 53^a on the bracket 53 and through which stud a securing screw 35^a passes to hold the bracket on the carriage.

It has been pointed out that the computing mechanism disclosed herein is like that shown and described in the above mentioned Wahl patent, and it will be unnecessary for the purpose of my invention to illustrate or describe such mechanism in detail except in so far as concerns parts thereof which are necessary to an understanding of the present invention. Therefore the illustration has been materially simplified by omitting many parts of the machine disclosed in said Wahl patent.

The main truck for the calculating mechanism comprises a bar 54 mounted and connected to the typewriter carriage to travel therewith. Thus, said bar carries bracket arms 55 connected by screws 56 to feet 57

formed on the brackets 37 and 53 which project forwardly from the carriage 13. So-called vertical totalizers 58, 59, 60, 61 and 62 are detachably and adjustably 5 mounted on the truck bar 54. Any desired number of these totalizers may be employed, five being shown in the present instance. Each totalizer carries registering mechanism including a series of gear wheels 63 10 and a series of number wheels 64. As a totalizer passes step-by-step through the computing zone the wheels 63 thereof are brought successively into mesh with a master wheel 65 controlled from the numeral keys 2. The extent the master wheel 65 and meshing gear wheel 63 rotate at each actuation of a key 2 depends on the particular numeral key depressed.

In addition to the vertical totalizers referred to, the machine is provided with a cross or jumping totalizer 66 which accumulates the sum registered on the series of vertical totalizers. This totalizer 66 is like the vertical totalizers and includes gear wheels 67 and a series of number wheels 68. The wheels 67 are brought successively into mesh with a master wheel 69, turned by the actuator at each depression of a numeral key 2 the same extent that the master wheel 65 is turned. The cross totalizer is carried by a cross truck which in the present instance is constructed and mounted like that disclosed in my Patent No. 1,464,095 dated Aug. 7, 1923. Said truck comprises a bar 70 on which 25 the cross-foot totalizer is detachably mounted. This bar is supported to move longitudinally by grooved bearing rollers 71 that travel on rods 72 secured to the frame. The trucks or carriages 54 and 70 are sometimes called "decimal carriages" because they determine by their positions at the time the decimal order in which the calculation, due to an operation of a numeral key 2, will occur.

In the hereinbefore mentioned Wahl patent, automatically operating connecting means between each vertical totalizer and the cross truck or carriage are provided for intermittently picking up the cross carriage and releasing it for alternate forward and back movements during a single travel of the main truck or carriage in one direction. In said patented construction the right-hand side plate of each of the vertical totalizers is formed with a fixed engaging projection 73 which is adapted to coat with an upwardly extending hook-like projection or tooth 74 on a so-called pick-up beam 75. A laterally projecting headed screw stud 76, fixed to 50 the beam 75, is received in a short horizontally disposed bearing slot 77 in a bracket arm 78 secured to the cross truck bar 70. This construction enables the beam 75 to receive a pivotal movement on the bracket and 55 also affords a limited relative sliding move-

ment between the two against the action of a contractile buffer spring 79, connected at one end to a pin 80, carried by the beam 75 and at its other end to the bracket arm 78. It will be observed that the force of the spring is directed in a line above the stud 76, and therefore tends to turn the beam around the center of said stud and elevate the inner hook-carrying end of the beam, and also tends to maintain the stud seated at 75 the right-hand end of the slot 77. This last mentioned function of the spring is to provide a cushion between each connected vertical totalizer and the cross truck as the latter is picked up by the former, especially in the rapid movement of the carriage under the action of the usual tabulator keys and when the carriage is moved by hand after depressing one of the carriage release keys 80 85 or 33.

A forwardly projecting pin 81 extends from the pick-up beam 75 and projects through an enlarged opening in a pick-up guard or locking beam 82, to be herein-after more fully described. The pin 81 after passing through the opening in the pick-up guard, extends into a slot 83 in a fixed plate 84. A part of the lower wall of the slot 83 is formed by the upper edge of an auxiliary plate 85 adapted to be 90 adjusted along the plate 84 and secured in place thereon by screws 86. The upper edge of the plate 85 has a depression 87 therein which, when the parts are in the normal position, is beneath the pin 81. This permits the pin 81 to move down into the depression 87 as the engaging projections 73 on the vertical totalizers move successively over the beveled face of the tooth or hook 74 and depress the pick-up beam in the backward travel of the main carriage 54. The slot 83 throughout all other parts thereof is of a width corresponding substantially to the diameter of the pin 81, and the walls of the slot therefore restrain the pin against free 95 up and down movement. The left-hand portion of the slot 83 is formed with a cam 88 with which the pin 81 coacts as the pick-up beam is carried along with the main carriage by a projection 73 on a vertical totalizer. 100 The effect of engaging the cam 88 is to move the pin 81 and the hook carrying end of the beam down, thus disengaging the hook 74 from the totalizer and enabling the cross truck 70 and the beam to be returned to the right independently of the main truck or carriage. A spring 89 is effective to bring about this independent return movement of the cross truck and the parts connected therewith. Said spring is connected at one 105 end to a pin 90 on the stationary frame plate 91, and at the other end to a pin 92 on the truck 70; the intermediate looped portion of the spring passing around a pulley 93 on the supporting frame. The cross truck 110 115 120 125 130

when released as described will be moved rapidly to the right by the spring 89 until arrested by the bar 94 (adjustably secured to the cross truck) striking a member 95 and 5 forcing it against the fixed frame plate 96.

The pick-up guard 82, hereinbefore referred to, is provided to automatically coact at its free end with the right-hand face of the projection or pick-up lug 73 on a vertical 10 totalizer when the hook or tooth 74 engages the opposite side of said projection, the two thus constituting an interlock that prevents a relative movement between the main truck and cross-truck in either direction of the 15 travel.

A more complete detail description of the construction and operation of the pick-up guard is deemed unnecessary, except to point out that it is automatically actuated and operates in conjunction with the pick-up beam 20 to insure the proper positioning of the cross truck in a decimal position corresponding to that of a vertical totalizer when the latter is in the computing zone.

25 The computing mechanism as thus far described, except as specifically indicated, is the same or substantially the same as that disclosed in the Wahl patent referred to above.

It will be understood that ordinarily in the 30 operation of the machine, as a vertical totalizer approaches the computing zone to bring a wheel 63 thereof into mesh with the master wheel 65, the pick-up beam 75 will be engaged by the projection 73 on a vertical 35 totalizer, causing the cross truck and cross totalizer 66 to travel in unison with the main truck or carriage. As said connected vertical totalizer passes out of the computing zone and beyond the master wheel 65 the pin 40 81 reaches the cam 88 and releases the pick-up beam, thereby enabling the cross-truck and totalizer 66 to be returned to the right by the spring 89. This intermittent forward and back movement of the cross truck 45 and totalizer takes place as each vertical totalizer passes through the computing zone, even when no actuation of the vertical totalizer is effected. This, therefore, results in unnecessary forward and back movements 50 of the cross truck and totalizer, with consequent unnecessary wear, liability of injury thereto, and the production of a clattering noise, especially under the rapid movements of the main carriage by hand or under control 55 of the tabulator. Let it be assumed, for example, that the main carriage is in the extreme right-hand position, and the operator desires to operate only the last or fifth totalizer 62. This may be brought about by depressing either of the carriage release keys 32 or 33 and moving the carriage to the proper position by hand, as is usually the case. The consequence ordinarily of moving 60 the main carriage in the manner described 65 is to alternately pick up and release the cross

truck for free return movement as each vertical totalizer passes through the computing zone, there being eight unnecessary forward and back movements of the cross truck in the example specified. Of course, when 70 more vertical totalizers are employed, and as many as thirty are sometimes used, there is apt to be a greater number of unnecessary forward and back movements of the cross truck, and a consequent increased clattering 75 noise and liability of injury.

In accordance with my present invention I overcome these difficulties, and provide improved means that are automatically actuated at each operation of a carriage release 80 key to hold the cross-truck against return movement to its normal position. The cross-truck is thus held so long as pressure is maintained on the release key, and until the main carriage has been positioned to bring the 85 proper vertical totalizer, say 62, in proper position to receive a registration therein. The operator then releases the depressed release key and the pick-up mechanism is then effective to carry the cross truck in unison 90 with the main truck and bring about an automatic return of the cross truck when the totalizer 62 passes out of the computing zone, thus causing the cross truck to make one forward and one backward movement 95 instead of ten, as would ordinarily be the case in the example given.

In the present construction the cross truck is provided with a bracket 97 adjustably secured to said truck by screws 98 which pass 100 through elongated openings in the foot piece of said bracket. Projecting up from the foot piece of the bracket is an engaging projection 99. A lever 100 of the first order, shown in detail in Fig. 3, is provided at one 105 end with an integral detent or hook-like engaging member 101, whereas the opposite end of the lever is provided with an anti-friction roller 102. The lever, intermediate its ends, is provided with a bearing sleeve 110 103 which, as shown clearly in Fig. 4, is mounted on the enlarged portion 104 of a headed screw 105 received at its threaded end in the usual main fixed supporting bar 106 of the computing attachment. The screw 115 105 is a special screw which replaces a screw usually employed at this point to hold the member 107 on the supporting bar. It will be seen from this figure that the detent-carrying arm of the lever 100 is arranged above the engaging member 99 and that the relation of the parts is such that when the cross truck is in its advanced position, as indicated in Figs. 2 and 4, and the detent is depressed, it will engage said member 99 120 and hold the truck against return movement until the detent is released.

The means by which the detent is controlled for the purpose stated are as follows:

A contractile spring 108 is fastened at one end to the detent-carrying arm of the lever 100 and tends to turn said lever clockwise and bring the detent into effective position. 5 The lower end of the spring may be anchored at a suitable point; in the present instance to a pin 109 secured to the stationary frame plate 91. Mounted on the typewriter carriage directly above the anti-friction roller 102 and co-acting therewith, is a controlling member 110 in the nature of a bar, blade or plate that extends substantially throughout the length of the carriage, so that it may contact with said roller 102 at any point in the 10 travel of said carriage. This bar is mounted to turn on its longitudinal axis by being fixed at its front edge portion to a parallel rock shaft 111. Said shaft is mounted to turn in bearings 112 in the brackets 37 and 20 53; the shaft at its right-hand end extending through and beyond the bracket 37. This end of the shaft has a crank arm 113 secured thereto, the free end of which extends up into the path of the release key 33 as the latter is depressed. The opposite 25 end portion of the shaft has a corresponding crank arm 114 secured thereto, said arm extending into the path of the release key 32. The upward motion of the arm 114 is limited by a stop pin 115 projecting inwardly from the bracket 53 into the path of said arm. A spring 116 is coiled around the shaft 111 and bears at one end against the pin 115 and at the other end against 30 35 the arm 114. The force of this spring tends to turn the rock shaft 111, bring the arm 114 against the pin 115 and turn the bar 110 down. The power of this spring is sufficient to overcome the power of the spring 40 45 108 and normally maintain the detent 101 out of the path of the engaging member 99 on the cross truck. When, however, the operator depresses either release key 32 or 33 it will coact with the associated crank arm and rock the shaft 111 against the force of its spring 116. This rocks the bar 110 up and the roller 102 bearing against said bar will follow it under the action of the spring 108. The effect of this is to lower the beveled 50 55 edge of the detent 101 into the path of travel of the engaging member 99 on the cross truck. The carriage having been released the operator moves it to the left, and as the first vertical totalizer, say 58, approaches the computing zone the pick-up lug 73 on said totalizer will engage the pick-up beam and cause the cross truck to be moved to the left with the main carriage. The cross truck continues to move with the main carriage until the pin 81 has been fully depressed by the cam 88 to release the pick-up beam from the engaged lug 73 to permit an independent return movement of the cross truck to normal position. As shown 60 65 in the present instance I have so constructed and arranged the parts that they are nicely timed so that the detent 101 does not engage the member 99 until the pin 81 is slightly beyond the releasing position shown in Fig. 2. It is possible to do this by reason of the fact that at the rate of speed at which the main carriage is moved in practice there is a slight overthrow of the cross truck to the left beyond the position shown in Fig. 2 after the pick-up beam has been moved to the releasing position shown in this figure. This overthrow is relied upon to bring about an engagement between the detent 101 and the member 99, and it is due to this requirement for a nice timing of the parts that the member 99 is made adjustable. The purpose in engaging the detent by an overthrow of the cross truck as stated, is to be assured in every instance that the engaging tooth 74 on the pick-up beam is moved and held down out of the path of the lugs 73 on the vertical totalizers when the cross truck is locked or held against return movement, otherwise injury to the machine might result. For example, if the detent 101 should hold the cross truck against return movement when the pin 81 is, say, half-way down the cam 88, then the engaging projection 74 on the pick-up beam would be maintained in the path of the projections 73 and injurious results might follow should the operator attempt to return the main carriage at this time. By relying on a slight overthrow of the cross truck to bring about an engagement of the detent 101 this difficulty is overcome. The operator having advanced the main carriage as stated, and locked the cross truck in its advanced position, continues to advance the main carriage until, say, the last totalizer 62 is positioned to receive a registration therein as indicated, for example, in Fig. 2. The operator now releases the depressed key 32 or 33, reestablishing connection with the escapement mechanism to hold the main carriage in the position to which it has been moved. The release of the depressed key 32 or 33 enables the bar 110 to be elevated by the spring 116 and the spring 108 causes the end of the lever 100 carrying the roller 102 to follow up the bar and release the detent from engagement with the cross truck. The latter is now free to return, but in moving back immediately causes the pick-up beam to be cammed up into operative position and the projection 74 thereon after dropping back a few spaces reaches the lug 73 on the totalizer 62, and connection between said totalizer and the cross truck is established and further return movement of the cross truck is prevented. The operator then proceeds to effect a registration in the totalizer 62, which results in a like registration being effected in the cross totalizer 66. As the totalizer 62 reaches the sub-units position after registering therein the pick-up beam 130

is automatically released and the cross truck returns to normal position. One forward and one backward movement of the cross truck instead of ten was effected in the 5 specific example referred to.

In the present instance I have enclosed 10 various parts of the computing mechanism in housings. Thus many parts of the machine that were formerly exposed are included in housings comprising side members 117, 118, 119 and 120 preferably of cast metal and to which are attached by screws 121 sheet metal cover plates 122 and 123. The construction presents a neater 15 appearance than heretofore and better protects the working parts against interference, injury and the admission of dust thereto.

In order to make the machine as a whole 20 more compact than heretofore I have provided a special top plate 124 for the typewriting machine which does not extend as far forward as in said prior machines. I also have provided a special detachable 25 corner post 125 at the right-hand forward corner of the typewriting machine, the upright portion of which post is off-set rearwardly beyond the point which the corresponding corner post formerly occupied. This enables me to reduce the fore-and-aft 30 dimensions of the machine at this portion thereof where the cross foot mechanism is situated.

The carriage release keys and their 35 connections disclosed herein enable such keys to be mounted further forward and at a higher elevation than heretofore, where they are more readily accessible to the operator.

The brackets 37 and 53 with the parts 40 carried thereby not only provide for a firmer and more rigid connection of the parts with the frame of the typewriter carriage but facilitate the addition of the computing mechanism to the typewriter as an attachment to the latter.

45 What I claim as new and desire to secure by Letters Patent is:—

1. In a computing machine, the combination 50 of a main carriage or truck, a cross truck, pick-up mechanism for causing the cross truck to travel in unison with the main truck and to return relatively thereto to normal position, and key controlled engaging means comprising two cooperative members one on the cross truck and the other controlled by said key, the construction and arrangement of the parts being such that the said two engaging members are brought into engagement by an overthrow of the cross truck after it is released 55 for relative return movement.

2. In a computing machine, the combination 60 of a main carriage, a cross totalizer, automatically operating pick-up mechanism for causing said cross totalizer to move in unison with the main carriage and to

return to normal position independently thereof, and key controlled engaging means for holding said cross totalizer against return movement to normal position when it is released by its pick-up mechanism, the 70 construction and arrangement of the parts being such that said engaging means are brought into engagement only by an overthrow of the cross totalizer after it is released by the pick-up mechanism. 75

3. In a computing machine, the combination 80 of a main carriage, a release key therefor, a jumping carriage, means for effecting forward and backward travel of the jumping carriage during a single travel of the main carriage in one direction, and controlling means controlled by said release key for rendering said last mentioned means ineffective to bring about a backward movement of the jumping carriage, the effectiveness of said controlling means depending on the depression of said release key and a forward overthrow of the jumping carriage. 85

4. In a computing machine, the combination 90 of a main carriage; a jumping carriage; automatically operating pick-up mechanism for effecting a movement of the jumping carriage in unison with said main carriage and for permitting an independent return movement of the jumping carriage to normal position, said pick-up mechanism comprising pick-up lugs on the main carriage, a pick-up beam, and means for automatically disconnecting the beam from the engaged lug to permit the independent return movement of the jumping carriage; and a key controlled detent operative to prevent an independent return movement to 95 normal position of said jumping carriage, the construction and arrangement of the parts being such that the detent when in effective position engages the jumping carriage only by an overthrow of the latter after the pick-up beam has been disengaged 100 from a lug. 105

5. In a computing machine, the combination 110 of a carriage carrying a plurality of vertical totalizers; a release key carried by said carriage; a jumping totalizer; automatically operating means for picking up the jumping totalizer as a vertical totalizer approaches the computing zone and for releasing it for return movement when the computing zone is passed; and means controlled by said release key for preventing a return movement of said jumping totalizer, said last mentioned means comprising a detent maintained ineffective when the release key is in the normal position and moved to effective position by the act of depressing the release key and maintained in effective position as long as the release key remains depressed, the construction and arrangement of the parts being such that said 115 120 125 130

detent when in effective position is engaged only by an overthrow of the jumping totalizer and after it is released from control of its pick-up mechanism.

5   6. In a computing machine, the combination of a carriage, a release key therefor, a controlling member carried by the carriage and controlled by said release key, a detent carried by a fixed part of the machine and controlled by said controlling member, a jumping totalizer, automatically operating means for moving said totalizer forward and backward during the travel of the carriage in one direction, and means operatively connected with said totalizer and with which said detent co-acts to prevent a return movement of the jumping totalizer to normal position when the release key is maintained depressed, the construction and arrangement of the parts being such that said detent when in effective position is engaged only by an overthrow of the jumping totalizer and after it is freed for independent backward movement to normal position.

25 7. In a computing machine, the combination of a main carriage, a cross truck, automatically operating pick-up mechanism for causing the cross truck to travel in unison with the main carriage and to return to normal position independently thereof, a detent for preventing an independent return of the cross truck to normal position, a release key carried by the main carriage, a lever by which said key is carried, a second lever having an arm to free the main carriage from control of its escapement mechanism, a link intermediate said levers, and means controlled by said release key for controlling the movement of the detent into and out of effective position.

8. In a computing machine, the combination of a main carriage, a cross truck, automatically operating pick-up mechanism for causing the cross truck to travel in unison with the main carriage and to return to normal position independently thereof, a detent for preventing an independent return of the cross truck to normal position, a release key carried by the main carriage, a lever by which said key is carried, a second lever having an arm to free the main carriage from control of its escapement mechanism, a rock shaft on the main carriage, a crank arm on said rock shaft with which said release key co-acts, and means controlled by said rock shaft for controlling the movement of said detent into and out of effective position.

60 9. In a computing machine, the combination of a main carriage, a cross truck, automatically operating pick-up mechanism for causing the cross truck to travel in unison with the main carriage and to return to normal position independently thereof, a detent for preventing an independent return of the cross truck to normal position, a release key

carried by the main carriage, a lever by which said key is carried, a second lever having an arm to free the main carriage from control of its escapement mechanism, a rock shaft on the main carriage, a crank arm on said rock shaft with which said release key co-acts, a plate on said rock shaft that extends substantially throughout the width of the carriage, and a lever mounted on a fixed part of the machine and with which said plate co-acts at any point in the travel of the main carriage, said lever carrying the detent. 70 75

10. In a computing machine, the combination of a main carriage, a carriage release key carried thereby, a cross totalizer, pick-up mechanism for causing the cross totalizer to travel in unison with the main carriage and return to normal position independently thereof, a lever of the first order fulcrumed on a fixed part of the machine and formed with an integral detent operative to prevent a return movement of the cross totalizer to normal position, and a pivoted bar mounted on and extending substantially throughout the width of the carriage and controlled by said release key for controlling the movement of said lever and thereby control the movement of the detent into and out of effective position. 80 85 90 95

11. In a computing machine, the combination of a main carriage, a carriage release key carried thereby, a cross totalizer; pick-up mechanism for causing the cross totalizer to travel in unison with the main carriage and return to normal position independently thereof, a lever of the first order fulcrumed on a fixed part of the machine and having a detent at one end thereof operative to prevent a return movement of the cross totalizer to normal position, a bar carried by said carriage and mounted to turn on its longitudinal axis on the carriage for independent movement thereon and which is controlled in its independent movement by said release key and co-acts with the other end of said lever to control the movement of said detent into and out of effective position. 100 105 110

12. In a computing machine, the combination of a main carriage, a carriage release key carried thereby, a cross totalizer, pick-up mechanism for causing the cross totalizer to travel in unison with the main carriage and return to normal position independently thereof, a lever of the first order fulcrumed on a fixed part of the machine and having a detent at one end thereof operative to prevent a return movement of the cross totalizer to normal position, a roller at the other end of said lever, a spring which tends to move said lever and bring the detent thereon into effective position, and a bar pivoted on said carriage for independent movement thereon and controlled in such independent movement by said release key. 130

said bar co-acting with said roller and controlling the movement of said lever to render the detent effective by withdrawing the bar on the depression of a release key and enabling said spring to move the lever and detent to operative position.

13. In a computing machine, the combination of a main carriage, a carriage release key carried thereby, a cross totalizer, pick-up mechanism for causing the cross totalizer to travel in unison with the main carriage and return to normal position independently thereof, a lever of the first order fulcrumed on a fixed part of the machine and having a detent operative to prevent a return movement of the cross totalizer to normal position, and a bar which extends substantially throughout the length of the carriage and has an independent pivotal movement thereon, said bar being controlled by said release key and coacting with said lever to control its movement and determine the effectiveness of the detent, said bar when in the normal position restraining the lever against moving the detent into effective position.

14. In a computing machine, the combination of a main carriage, a carriage release key carried thereby, a cross totalizer, pick-up mechanism for causing the cross totalizer to travel in unison with the main carriage and return to normal position independently thereof, a lever fulcrumed on a fixed part of the machine and having a detent operative to prevent a return movement of the cross totalizer to normal position, and a rock shaft on the carriage having means which co-act with said lever at any point in the travel of the carriage to control the movement of said lever and thereby control the movement of the detent into and out of effective position, and a crank arm on said rock shaft with which said release key co-acts to control the rocking movement of said shaft.

15. In a computing machine, the combination of a carriage, a release key therefor, a rock shaft controlled thereby, a controlling plate carried by said rock shaft and extending substantially throughout the width of the carriage, a detent carried by a fixed part of the machine and controlled by said controlling plate at any point in the travel of the carriage, a jumping totalizer, automatically operating means for moving the totalizer forward and backward during the travel of the carriage in one direction, and means operatively connected with said jumping totalizer and with which said detent co-acts to prevent a return movement of said totalizer to normal position so long as said release key is maintained depressed.

16. In a computing machine, the combination of a carriage carrying a plurality of vertical totalizers, a release key carried

by said carriage; a jumping totalizer; automatically operating means for picking up the jumping totalizer as a vertical totalizer approaches the computing zone and for releasing it for return movement to normal position when the computing zone is passed; and means controlled by said release key for preventing a return movement of said jumping totalizer, said last mentioned means comprising a rock shaft carried by the carriage and controlled by said release key, a plate-like controlling member carried by said shaft and extending substantially throughout the width of the carriage, a detent carried by a fixed part of the machine and controlled by said controlling member, and an engaging member that moves with the jumping totalizer and with which the detent is adapted to coact to prevent a return movement of the carriage to normal position.

17. In a computing machine, the combination of a carriage carrying a plurality of vertical totalizers; a release key carried by said carriage; a cross truck; a jumping totalizer carried by said cross truck; automatically operating means for picking up said cross truck as a vertical totalizer approaches the computing zone and for releasing it for return movement when the computing zone is passed; and means controlled by said release key for preventing a return movement of said cross truck to normal position, said last mentioned means comprising a plate-like controlling member pivoted to turn on its longitudinal axis on the carriage and controlled by said release key, a lever mounted on a fixed part of the machine and with which said controlling member co-acts at any point in the travel of the carriage, a detent carried by and formed as a part of said lever and controlled in its movement into and out of effective position by said controlling member, and an adjustable engaging projection on said cross truck and with which said detent is adapted to co-act to prevent a return movement of the cross truck to normal position.

18. In a computing machine, the combination of a main carriage, a carriage release key carried thereby, a cross totalizer, pick-up mechanism for causing the cross totalizer to travel in unison with the main carriage and return to normal position independently thereof, a lever of the first order fulcrumed on a fixed part of the machine and formed with an integral hook-like detent at one end thereof and provided with a roller at its other end, a spring which tends to turn said lever and move the detent thereon into effective position, a spring returned rock-shaft on the carriage, a blade on said rock-shaft which co-acts with said roller at any point in the travel of the carriage and controls the lever to normally

9

maintain the detent in ineffective position, and a crank arm on said rock shaft with which said release key co-acts to turn the shaft against the force of its spring when the key is depressed and thereby permit the spring for the lever to move it and bring the detent into effective position.

Signed at the borough of Manhattan, city

of New York, in the county of New York and State of New York, this 7th day of Dec. 10 A. D. 1923.
